UNITED STATES PATENT OFFICE.

ALFRED MALACHI GALLERY, OF TORONTO, ONTARIO, CANADA.

STREET INDICATOR FOR STREET-RAILWAY SYSTEMS.

1,425,583.

Specification of Letters Patent. Patented Aug. 15, 1922.

Application filed March 23, 1922. Serial No. 546,007.

To all whom it may concern:

Be it known that I, ALFRED MALACHI GALLERY, a subject of the King of Great Britain, residing at Toronto, in the county of York, 5 Province of Ontario, Canada, have invented certain new and useful Improvements in Street Indicators for Street-Railway Systems, of which the following is the specification.

10 My invention relates to improvements in street indicators for street railway systems and the object of the invention is to devise a simple construction of indicator which upon the pressing of a button by the conductor will automatically indicate each successive street as the car approaches each street and it consists essentially of the arrangement and construction of parts as hereininafter more particularly explained.

15 Fig. 1 is a perspective view of my street indicator.

Fig. 2 is a plan view of my street indicator with the containing casing removed and showing in diagram the wiring connections by which it is operated.

20 Fig. 3 is a front elevation of the parts shown in Fig. 2, the wiring connections being removed.

Fig. 4 is a cross sectional view on line 30 4—4, Fig. 2.

Fig. 5 is a cross sectional view on line 5—5, Fig. 2.

Fig. 6 is a cross sectional detail on line 35 6—6, Fig. 3, looking in the direction of arrow.

Fig. 7 is a perspective detail of a semi-circular face cam and adjacent parts employed in connection with my device.

Fig. 8 is a detailed view of the driving 40 connection between the sprocket wheels and the spool shafts.

Fig. 9 is a detail view of the flange 50.

Fig. 10 is a detail view of the hook 66.

Fig. 11 is an enlarged plan view of the 45 driving mechanism shown in Fig. 1.

Fig. 12 is an enlarged elevation of the parts shown in Fig. 11.

50 In the drawings like characters of reference indicate corresponding parts in each figure.

1 indicates my indicator casing which is

provided with an exhibiting orifice 2 through which the names of the streets of the route successively appear when the operating button is pressed as the street car 55 approaches each street.

I will now describe the interior mechanism which is contained within the casing 1.

3 indicates a base plate which is located 60 within the casing 1 and from which extends upwardly standard plates 4, 5 and 6. The plates 4, 5 and 6 are connected together in proximity to their upper ends by tie bolts 7 and 8.

9 and 10 are shafts journaled in plates 4 and 5 and located vertically one above the other.

11 and 12 are flanged spools which are secured to the shafts 9 and 10 and on which 70 is wound a fabric band 13 which is adapted to be fed by mechanism, which I will hereinafter describe from one spool to the other.

Upon the band 13 is inscribed the names of the streets such as indicated at 14, the 75 names of the streets being spaced apart so that the street name appears opposite the exhibiting orifice 2 at each movement of the band 13.

In order that sufficient tension may be 80 exerted on the band 13 I provide pressure rollers 15 mounted on spindles 16 journaled in arms 17 and 18 the upper arms being swung upon one of the bolts 8 and the lower arms on bolt 8^x as indicated in Fig. 4. The 85 rollers bear upon the upper surface of the band as it is wound on and off the spools 11 and 12.

19 and 19^x are rollers carried between the plates 4 and 5 and around which the band 13 90 passes so that it extends vertically at the inside of the exhibiting orifice 2.

20 and 21 are sprocket wheels which are mounted respectively upon the shafts 9 and 10, and the sprocket wheels 20 and 21 are 95 connected together by a sprocket chain 22.

23 is a main driving motor which may be of any suitable type, the main shaft 24 of which is provided with a pinion 25.

26 is a counter shaft provided with a gear 100 27 meshing with the pinion 25, and a pinion 28.

29 is a supplemental counter shaft upon which is mounted a gear 55 meshing with the pinion 28.

To the lower shaft 10 is secured a pair 5 of gears 31 and 32. 33 is a shaft journalled in the plate 5 and in a bracket 34 extending from such plate.

36 is a sleeve which is slidably mounted upon the shaft 33 and provided at one end 10 with a pinion 34^x and at the opposite end with an annular groove 35.

37 is a shaft which is also journalled in the plate 5 and in the bracket 34 and upon which is mounted a broad gear pinion 38. 15 The gear pinion 38 meshes at one end with the gear 31 and at the opposite end with the pinion 34^x.

When the sleeve 36 is moved longitudinally upon the shaft 33 the pinion 34^x is 20 carried out of mesh with the pinion 38 and into mesh with the gear 32.

By this means the drive of the shaft 10 is alternately reversed in the direction of rotation.

25 39 is an arm which is hingedly mounted at 40 so as to be capable of swinging in and out from the plate 5. The free end of the arm 39 is provided with a fork 41 which enters the groove 35 of the sleeve 36.

30 42 is a wire which is connected at one end by an eye 43 to the arm 39 and is connected at its opposite end to the plate 4 by a tension spring 44. The tendency of the spring 44 is to swing the arm 39 outward from the 35 plate 5.

45 is a short shaft extending outwardly from the plate 5 and provided with a squared portion 46.

47 is a squared sleeve slidably fitted upon 40 the squared portion 46 of the short shaft 45.

48 is an annular groove formed by flanges 49 extending from the sleeve 47. 50 is a semi-circular flange extending from one end 45 of the sleeve 47. The flange 50 is provided with a projecting finger 51.

52 is a semi-circular inclined face cam-way extending above the short shaft 45 and concentric with the center thereof.

53 is a gear secured to the short shaft 50. 33^x is a stub shaft carried by the plate 5. 33^x is a pinion formed integral with the gear 30 and meshing with the gear 55.

28^x is a pinion also mounted on the shaft 26.

55 56 is a lever which is hingedly mounted at 57 upon the base plate 3, the upper end of the lever 56 is provided with a fork 58 engaging the annular groove 48.

59 is a standard in which the short shaft 60 45 is journalled, the opposite end being journalled in the plate 5. 35^x is a stub shaft carried by the standard 59. 37^x and 37^y is a gear and pinion formed integral and mounted upon the shaft 35^x the gear

37^x meshing with the pinion 28^x and the 65 pinion 37^y meshing with the gear 53. By this means the shaft 45 is driven in the direction of arrow (see Fig. 2) carrying the finger 51 off with the high end of the semi-circular face of the cam 52.

The lever 56 is spring held in its normal position by a spiral spring 60 extending between the standard 59 and the lever 56.

The arm 39 is provided with an inwardly extending tongue 61. The tongue 61 extends 75 between the semi-circular flange 50 and the plate 5. The flange 50 is provided with an edge groove 50^x into which the end of the tongue 61 extends. When the short shaft 45 is rotated in the direction of arrow the 80 finger 51 is carried off the end of the cam 52 so as to strike the tongue 61 thereby forcing the sleeve 47 longitudinally and swinging the lever 56 on its hinged center 57 against the pressure of the spring 60 toward 85 the plate 5. The tongue 61 is held in the groove 50^x during half a revolution of the shaft 45 and by further rotation of the flange 50 allows the arm 39 to swing outward on its hinge 40, as the tongue 61 passes 90 out of engagement with the grooved portion 50^x of the flange 50, or in other words, such operation carries the semi-circular flange 50 out of engagement with the inwardly extending portion or tongue 61 of the arm 95 39. Such arm 39 being then swung outward by means of the tension spring 44.

It will of course be understood that the tension spring 44 is held in tension by means of the semi-circular flange 50 bearing 100 against the tongue 61 so as to hold the arm 39 against the plate 5.

As before stated the arm 39 is provided with a fork 41 engaging the annular groove 35 of the sleeve 36.

It will thus be seen that when the arm 39 is released as above described such arm will carry the pinion 34^x out of engagement with the pinion 38 and into engagement with the gear 32 thereby driving the shaft 10 in the 110 opposite direction.

In order that there may be alternately a direct drive between the sprocket gears 20 and 21 and the shafts 9 and 10 I have provided toothed wheels 62 and 63 which are 115 mounted upon the shafts 9 and 10 and are connected to be integral with the spools 11 and 12.

64 and 65 are arms each provided with a perforation 65^x. 66 is a hook preferably 120 formed of wire which is bent concentrically with the corresponding wheel 62 or 63, one end of the wire being bent inward radially of the wheel at 67 to engage the teeth of such wheel, the opposite end being bent at 125 right angles 68 so as to pass through the perforations 65^x and through an orifice 69 formed in each gear 20 and 21 the extreme

end of the wire being bent radially and then inward to pass through a perforation 65° forming a crank end.

It will be noted on referring to Fig. 8 that the end of the portion 68 being bent into a crank, as the sprocket wheel 21 is rotated in a forward direction the lower hook 65 is thrown into engagement with the tooth wheel 63 and the upper hook 65 out of engagement with the tooth wheel 62 thereby forming a driving connection for rotating the band 13 in a downward direction or direction indicated by arrow in Fig. 3. When the sprocket wheel 21 is rotated in the opposite direction the upper hook 65 is thrown into engagement with the toothed wheel 62 thus rotating the spool 20 and allowing the spool 21 to idle or run free.

71 is a starting motor, the main shaft 72 of which is provided with an arm 73 having an out turned portion 74.

75 is a vibrator provided with the usual coils 76 and armature 77. 78 is a curved arm which is secured at one end of the armature 77 and provided at its opposite or free end with an insulated latching piece 79.

80 is a shaft which is journaled in a bracket 81 and upon which is mounted a wheel 82. The wheel 82 is spring held from rotation by a tension spring 82^x (see Fig. 3).

83 is a catch the upper face of which is curved so as to radially slip by the insulated piece 79 in its upward movement and engage behind such catch piece.

84 is a contact finger also carried by the wheel 82. 85 is an arm extending radially from the shaft 80 and bearing upon the spring support 86 in its normal position.

87 and 88 are the terminals of the motor 71. 89 is a wire leading from the terminal 88. 90 is a battery. 91 is a wire leading from the terminal 87 to one terminal of the battery 90.

92 is a push button switch provided with stationary contacts 93 and 94 and a bridging contact 95. 96 is a wire leading to the other terminal of the battery 90 to the switch contact 94. The wire 89 leading from the terminal 88 extends to the other stationary contact 93 of the push button switch.

The band 13 opposite each street name is provided with a metallic contact piece such as indicated at 97, and 98 is an insulating block carried by the plate 4.

99 and 100 are contacts carried by the block 98 and spaced apart, such contacts being bridged by the contact piece 97 as it passes thereover during the revolution of the band 13.

101 is a battery. 102 is a wire leading from one terminal of the battery 101 to the contact 99. 103 is a wire leading from the other contact 100 to one terminal of the vibrator 75.

104 is a wire leading from the other ter-

minal of the vibrator to the opposite terminal of the battery 101. 105 is a pin extending upwardly from the base plate 3 and on which is swung an arm 106 provided with a metal contact 107. The opposite end of the arm 106 is provided with a fork 108 into which extends a pin 109 such pin being formed integral with the wire 42.

110 and 111 are opposing contacts between which the contact piece 107 is designed to swing to form a bridging connection between the contacts 110 and 111.

112 is a wire extending from the contact 110 and tapped into the wire 103 at its opposite end. 113 is a wire extending from the contact 111 and tapped into the wire 102 at its opposite end.

Having described the principal parts embodied in my invention I will now briefly describe the operation of the same.

As the car is travelling towards the next street intersection of the route the conductor presses the button 92 closing the circuit of the battery 90 by bridging the contacts 93 and 94. By this means the motor 71 is energized revolving in the direction of arrow, carrying the out turned portion 74 of the arm 73 rapidly against the spring supported arm 85.

By this means the spring support of the arm 85 is momentarily depressed by the downward pressure upon the arm 85. Since the arm 85 is released by reason of the out turned portion 74 of the arm 73 passing downward beyond such arm the arm 85 is thrown upward rotating the shaft 80 and the wheel 82. By this operation the catch piece 83 is carried upward in the direction of arrow so as to spring past and beneath the insulating latching piece 79.

By this movement the contact finger 84 is carried between the stationary contacts 84^x and 84°. The contacts 84^x and 84° form the terminal of the main motor circuit, such circuit being formed by the wire 113 leading from the contact 84^x to one of the terminals of the motor 23, a wire 114 leading from the contact plate 84° to the battery 115 and a wire 116 leading from the opposite terminal of the battery to the other terminal of the motor 23.

When this circuit is complete the motor 23 revolves driving the shaft 45 as hereinbefore described by means of the gears 28^x, 37^x, 37° and 53 and by means of the gears 28, 55, 33°, 30, 55^x, shaft 33 and gears 34^x and 31 driving the shaft 10 to carry the band 13 downward in the direction of arrow.

It will of course be understood that the sleeve 36 is feather keyed upon the shaft 33. As each contact 97 comes into bridging position with the contacts 99 and 100 the circuit of the vibrator 75 is closed through the wire 103 leading to one terminal of the vibrator, wire 104 leading from one terminal of the

battery 101 and wire 102 to the other terminal 99.

As the vibrator operates the insulated contact 79 is moved out of engagement with the latching contact 83 the spring 82* pulling the wheel back to its normal position carrying the contact 84 out of engagement with the stationary contacts 84^x and 84° thereby breaking the main motor circuit and stopping the movement of the band 13. This operation is repeated at every street intersection.

As the finger 51 travels up the camway 52 the tongue 61 engages the groove 50^x of the flange 50 controlling the movement of the arm 39. As soon as the tongue 61 passes out of the groove 50^x the arm 39 is carried by a quick movement away from the plate 5 and the pinion 34^x into engagement with the gear 32.

As soon as the finger 51 passes over the end of the camway 52 it strikes the upwardly extending finger 61 so as to carry the arm 39 inward towards the plate 5 and the pinion 34 into the reversing position, simultaneously with this movement the wire 42 is pulled by the arm 39 swinging the arm 106 so as to carry the contact 107 between the contacts 110 and 111 to momentarily close the vibrator circuit thereby raising the insulated latch piece 79 freeing the latching finger 83 so as to break the main motor circuit. When the band 13 arrives at the opposite end of its movement the arm 39 is again released and carried out by the spring 44.

This movement swings the contact 107 in the opposite direction swinging the contacts 110 and 111 to again close the vibrator circuit and break the main motor circuit.

From this description it will be seen that I have devised a street indicator which may be readily controlled by means of a push button operated by the conductor so that it will indicate the streets of a route successively and in which the band carrying the indicating street names will return to its normal position automatically at the end of the route.

50. What I claim as my invention is:

1. In a street indicator, a carrier on which a series of street names comprising a car route are indicated, two electric circuits each having a switch opening each provided with normally open switch contacts, a main motor located in one of such circuits, a driving connection between the motor and the carrier, a supplemental starting motor located in the other of such circuits, a push button for closing the normally open switch of the supplemental motor circuit, and means operated by the supplemental circuit for closing the circuit of the main motor.

2. In a street indicator, a carrier on which a series of street names are indicated, a

main electric circuit and a supplemental electric circuit each having a switch opening, a main motor located in the main electric circuit, a train of gear operated thereby for driving the carrier, a supplemental motor located in the supplemental circuit, a push button for closing the switch opening of the supplemental circuit, a movable contact for closing the switch opening of the main motor, circuit closing means operated by the supplemental motor for moving such contact to the closed position, and means operated by the carrier at each indicating position for automatically returning the contact to the open position.

3. In a street indicator, a carrier on which a series of street names comprising a car route are indicated, a main electric circuit, a main motor located in such circuit, a normally open switch also located in such main circuit, a train of gear operated by the motor for driving the carrier, a supplemental circuit having a normally open switch, a push button contact for closing the switch, a supplemental motor located in the supplemental circuit, a movable contact for the switch of the main motor circuit, a latching device actuated by the supplemental motor for holding the switch of the main motor circuit closed, and means adapted to release such latching device as the carrier comes to each indicating position.

4. In a street indicator, a carrier on which a series of street names comprising a car route are indicated, a main electric circuit, a main motor located in such circuit, a normally open switch located in the main circuit, a train of gear operated by the motor for driving the carrier, a supplemental circuit having a normally open switch, a push button contact for closing the switch, a supplemental motor located in the supplemental circuit, a movable contact for closing the switch of the main motor circuit, a latching device comprising a swinging member carrying a contact at one side of the centre of swing and coacting with the stationary contacts of the switch of the main motor circuit, a latching piece carried by the swinging member on the other side of the centre of swing, a latch engaging member located in the path of the latching piece, means operated by the supplemental motor for swinging the latching piece into engagement with the latch engaging member, and means operated by the carrier for moving the latch engaging member out of engagement with the latching piece as the carrier arrives at its indicating position.

5. In a street indicator, a carrier on which a series of street names comprising a car route are indicated, a main motor circuit provided with a normally open switch having opposing switch contacts, a main motor in such circuit, a train of gear operated by the

main motor for driving the carrier, a supplemental motor, a circuit therefor, a manually operated switch located in the supplemental circuit, an arm carried on the shaft of the supplemental motor, a rocking shaft, an arm extending radially from the rocking shaft into the path of the arm of the supplemental motor, a resilient support for the rocking shaft arm, a switch for closing the main motor circuit operated by the rocking of the arm, and automatic means for opening the switch as the carrier reaches each indicating position.

6. In a street indicator, a carrier on which a series of street names comprising a car route are indicated, a main motor circuit provided with a normally open switch having opposing switch contacts, a train of gear operated by the main motor and driving the carrier, a supplemental motor, a supplemental motor circuit, a normally operated switch located in the supplemental circuit, a rocking shaft, means operated by the rocking of the shaft for closing the switch of the main motor circuit, and means for periodically rocking the shaft operated by the rotation of the supplemental motor shaft.

7. In a street indicator, a carrier on which a series of street names comprising a car route are indicated a main motor, a main motor circuit provided with a normally closed switch having opposing switch contacts, a train of gear operated by the main motor and driving the carrier, a supplemental motor, a manually operated switch located in the supplemental motor circuit, a rocking shaft, a rocking member carried on the rocking shaft, a contact carried at one side of the rocking member coacting with the switch contacts of the main motor circuit, a latching piece carried upon the opposite side of the rocking member, a withdrawable latch piece engaging member, means for automatically operating the latch engaging member to withdraw as the carrier reaches the indicating position, and means operated by the supplemental motor for periodically rocking the shaft.

8. In a street indicator, a carrier on which a series of street names comprising a car route are indicated, a main motor, a main motor circuit provided with a normally open switch having opposing switch contacts, a train of gear operated by the main motor and driving the carrier, a supplemental motor, a manually operated switch located in the supplemental circuit, an arm carried on the arm of the supplemental motor shaft, a rocking shaft, an arm extending radially from the rocking shaft into the path of the arm of the supplemental motor, a resilient support for the rocking shaft arm, a rocking member carried on the rocking shaft, a contact carried at one side of

the rocking member coacting with the switch contacts of the main motor circuit, a latching piece carried on the opposite side of the rocking member, an electromagnet, a swinging armature therefor, an arm carried by the armature, a latch engaging member carried on the arm and with which the latching piece engages when swung upward, and means operated by the carrier for raising the latch engaging member out of the path of the latching piece to release the same as the carrier reaches the indicating position.

9. In a street indicator, a carrier on which a series of street names comprising a car route are indicated, a main motor, a main motor circuit provided with a normally open switch having opposing switch contacts, a train of gear operated by the main motor and driving the carrier, a supplemental motor, a manually operated switch located in the supplemental motor circuit, a movable switch member swung centrally upon a suitable support and provided with a contact, a movable engaging member adapted to engage the movable member at the other side of the centre of swing to hold such contact in its engaging position, an electromagnet, an armature coacting therewith upon which such engaging member is carried whereby the engaging member is carried out of its engaging position by the energizing of the magnet, and resilient means for drawing the movable contact out of its closed position when released by the engaging member.

10. In a street indicator, the combination with the main frame, of an upper and a lower shaft, a band upon which street names are indicated at suitable distances apart and adapted to be wound around the aforesaid upper and lower shafts, a pair of gears secured to the lower shaft, a broad pinion 105 engaging with one of the aforesaid gears at one end, a pinion engaging with the broad pinion, means for moving the engaging pinion out of engagement with the broad pinion into engagement with the other gear 110 of the aforesaid pair, a main motor, and means for driving the movable pinion therefrom.

11. In a street indicator, the combination with the main frame, of an upper and a lower shaft, a band upon which street names are indicated at suitable distances apart and adapted to be wound around the aforesaid upper and lower shafts, a pair of gears secured to the lower shaft, a broad pinion 115 engaging with one of the aforesaid gears at one end, a movable pinion engaging with the broad pinion, a lever swung upon the main frame and adapted to move the movable pinion, a driving motor, a driving connection between the motor and the movable pinion, and means operated from the driving motor for moving the pinion out of en-

gagement with the broad pinion into engagement with the disengaged gear of the aforesaid pair, and vice-versa.

12. In a street indicator, the combination with the main frame, of an upper and a lower shaft, a band upon which street names are indicated at suitable distances apart and adapted to be wound around the aforesaid upper and lower shafts, a pair of gears secured to the lower shaft, a broad pinion engaging with one of the aforesaid gears at one end, a movable pinion engaging with the broad pinion, a driving motor, a driving connection between the driving motor and movable pinion, a shaft mounted upon the main frame, a spring-pressed sleeve rotatable with and slidabale upon the shaft, a semi-circular flange extending from the sleeve having a tooth projection at one end, an arc-shaped cam carried by the main frame concentric with the shaft and inclined upward from one end with which the aforesaid tooth engages as the sleeve rotates, a lever hingedly mounted upon the main frame having a means at one end for engaging the movable pinion to move it, a tongue extending upwardly from the lever behind the aforesaid semi-circular flange, and tension means for drawing the lever tongue into bearing engagement with the flange.
13. In a street indicator, the combination with the main frame, of an upper and lower shaft journalled in the main frame, a spool carried upon each upper and lower shaft, an indicating band wound upon the spools, a pair of gears secured to one of said shafts, a broad pinion in engagement with one of said gears at one end, a movable pinion in engagement with the broad pinion and adapted to be moved out of engagement

therewith into engagement with the other gear of the aforesaid pair, a driving motor for the movable pinion, means operated by the driving motor for moving the pinion alternately in either direction to form a reverse drive, and engaging means between the upper and lower shafts and the corresponding spools whereby the upper shaft and spool are engaged and the lower shaft and spool disengaged when the drive is in one direction and vice-versa when the drive is in the opposite direction.

14. In a street indicator, the combination with the main frame, of an upper and lower shaft journalled in the main frame, a spool carried upon each upper and lower shaft, an indicating band wound upon the spools, a pair of gears secured to one of said shafts, a broad pinion in engagement with one of said gears at one end, a movable pinion in engagement with the broad pinion and adapted to be moved out of engagement therewith into engagement with the other gear of the aforesaid gear, a driving motor for the movable pinion, means operated by the driving motor for moving the pinion alternately in either direction to form a reverse drive, a sprocket driving connection between the upper and lower shafts, a toothed wheel formed integral with each spool, an arm carried by the toothed wheel, a rocking member carried in the arm and adapted at one end to extend circumferentially of the toothed wheel and to engage with the teeth thereof and on the opposite end to extend through the corresponding sprocket of the aforesaid sprocket connection and provided with a crank portion at such opposite end engaging with the sprocket.

ALFRED MALACHI GALLERY.
